CLAIM

The ornamental design for a combined nut holder and nut cracker, as shown and described.

DESCRIPTION

FIG. 1 is an exploded perspective view of a combined nut holder and nut cracker showing my new design;

FIG. 2 is a side elevational view of the nut cracker shown separately for clarity of illustration;

FIG. 3 is a bottom plan view of FIG. 2;

FIG. 4 is a top plan view thereof;

FIG. 5 is a front elevational view thereof, the opposite side being a mirror image;

FIG. 6 is a left side elevational view thereof;

FIG. 7 is a right side elevational view thereof; and

FIG. 8 is a bottom plan view thereof.
